UNITED STATES PATENT OFFICE.

THOMAS GUNNI SAXTON, OF LEXINGTON, KENTUCKY, ASSIGNOR OF FIFTY-ONE ONE-HUNDREDTHS TO CHARLES J. BRONSTON, OF LEXINGTON, KENTUCKY.

METHOD FOR PREPARING FIBERS.

No. 845,267.

Specification of Letters Patent.

Patented Feb. 26, 1907.

Application filed December 22, 1905. Serial No. 293,043.

To all whom it may concern:

Be it known that I, THOMAS GUNNI SAXTON, a citizen of the United States, residing at Lexington, in the county of Fayette and State of Kentucky, have invented new and useful Improvements in Methods for Preparing Fibers, of which the following is a specification.

This invention relates to a method and apparatus or machine for crushing or dismembering the stalk or woody part of hemp, jute, ramie, manila, or other similar fibers and removing therefrom all matter except the fiber by compressed air or other compressible gas delivered thereto to adapt the fiber for use in textile manufacture.

The preferred apparatus or machine in which the method is practiced embodies crushing or dismembering rolls preferably having spiral ribs or analogous surface projections to which the stalk or woody part of the hemp, jute, ramie, manila, or other similar fiber is fed, and these rolls may be disposed in multiple series in sequence to effectively separate the fiber and subject the latter to the action of compressed air, and thereby produce a superior fiber substance for general manufacturing purposes. To render the crushing or dismembering of the stalk or woody part certain and beneficial, particularly in view of the final cleaning of the fiber by the use of compressed air, it is preferred that the rolls have longitudinal sliding movement one with respect to the other. The compressed air is applied to the fiber at such point as to be most effective in performing a cleaning operation and to remove leaves or other parts detrimental to the use of fiber for textile purposes. In the use of air or gas for this purpose it is necessary that it be highly compressed before delivery or application, so that the expansion of the air or gas when liberated in the outlet means of the machine through which the fiber is passed will result in a more thorough and complete permeation of the fiber by the air or gas to drive out small particles of leaves or other material that may cling to the fiber.

In the accompanying drawings a preferred form of the apparatus or machine is illustrated, and therein—

Figure 1 is an end elevation of the apparatus, particularly showing the feeding-orifice

and portions of the rolls. Fig. 2 is a side elevation of the apparatus or machine, showing a part of the mechanism in dotted lines. Fig. 3 is a plan view of a pair of the rolls, showing the means for operating the same. Fig. 4 is a longitudinal vertical section through the center of the tubular outlet for the compressed air or gas. Fig. 5 is an enlarged transverse vertical section through the tubular outlet for the compressed air or gas. Fig. 6 is a detail horizontal section of a portion of the machine.

Similar numerals of reference are employed to indicate corresponding parts in the several views.

The numeral 1 designates a suitable inclosure, in which are disposed upper and lower pairs of rolls 2 and 3, as shown by Figs. 1 and 3 and clearly indicated as to position by Fig. 2. The rolls 2 and 3 are preferably formed with spiral ribs or projections by grooving said rolls, as at 4. It will be understood, however, that in some instances these rolls may have other surface projections, the object being to provide means for thoroughly and effectively crushing or dismembering the stalk or woody part of the material treated. The rolls 2 and 3 are respectively mounted on shafts 5 and 6, the one shaft 5 having keyed thereon a driving-gear 7, which is held in continual mesh with a similar gear 8 on one of the shafts 6, suitable driving means coöperating with either of the gears 7 or 8 to impart motion to one of the latter, and from the one gear engaged motion is transmitted to the other. On the opposite ends of the upper and lower pairs of shafts 5 and 6 are spur-gears 9 and 10, the spur-gears 9 meshing with the gears 10 immediately therebelow, as shown by Fig. 2; but the gears 9 and 10 do not mesh with each other. The object of this arrangement is to rotate the upper and lower pairs of rolls in proper directions, as indicated by the arrows shown in Fig. 2, and to facilitate the indrawing of the hemp, jute, ramie, manila, or other material into the apparatus or machine between the rolls. The upper rolls 2 preferably remain fixed so far as longitudinal movement thereof is concerned; but the lower pairs of rolls 3 have their shafts 6 slidingly disposed and operated by means which will be presently set forth to longitudinally shift the said lower rolls 3 in alterna-

tion with relation to the upper rolls 2 to institute a rubbing action and more thoroughly crush or dismember the stalk or woody part of the material fed to the apparatus or machine.

The mechanism for imparting longitudinal sliding movement in alternation to the rolls 3 embodies cam-wheels 11, one on each shaft 6, each of the cam-wheels being formed with a spiral cam-groove 12, and the grooves of both wheels are engaged by a horizontally-disposed arm 13, fixed on the upper end of a support 14, the latter having suitable means co-operating therewith for securing it to the frame of the machine. The grooves 12 of the cam-wheels 11 are so arranged in the prime organization of the machine that the rolls 3 will be longitudinally shifted in alternation, and such shifting action of the lower rolls 3 will take place without interfering in the least with the rotary movement of both the upper and lower sets of rolls or dismembering the gears 7 and 8 or the spur-gears 9 and 10 of the respective pairs of rolls. By the shifting operation of the lower rolls 3 it will be observed that the material treated will not only be subjected to a longitudinal crushing or mashing force when fed between the rolls, but also to a transverse dismembering operation or disintegration, with material advantage in setting the fiber free from the stalk or woody part of the material operated upon.

The front end of the machine or apparatus is formed with a transversely-extending feed opening or slot 15 of suitable dimensions, having a feed-hopper or guiding inclosure 16 arranged about the same. In longitudinal alignment with the hopper or inclosure 16 the opposite end of the apparatus or machine is provided with a suitable tubular outlet 17, which connects at its inner end with a compressed-air-applying trunk or device.

The compressed-air or gas applying trunk or device extends transversely across the rear end of the machine and involves in its organization a hollow inclosure 18, having a compressed-air conduit 19 connected to the center of one end thereof and adapted to be attached to any suitable air-compressing means or to a compressed-air or gas reservoir. Centrally disposed within the hollow inclosure 18 is an elongated outlet-opening 20, located between air or gas ducts 21, extending longitudinally of the air trunk or applying device and in communication with the conduit 19. The air or gas ducts 21 do not have communication with the outlet-opening 20, so that the fiber leaving the adjacent pair of rolls 5 and 6 may pass through the opening 20 into the inner terminal of the tubular outlet or guide 17. From the ducts 20 a series of small bores or orifices 22 extend at inner angles and communicate with the inner terminal of the tubular outlet or guide 17. The

orifices 22 of the upper and lower ducts are arranged at reverse angles or converge toward the center of the tubular outlet or guide 17, as clearly shown by Fig. 5, and the air or gas escaping from said orifices crosses or intersects and thereby passes through the fiber from above and below the latter. The orifices 22 of the upper and lower ducts also preferably have an inward angular trend from opposite extremities of the trunk or the ducts, as clearly shown by the arrows indicated in Fig. 6, so as to concentrate the leaves and other matter removed from the fiber toward the longitudinal center of the tubular outlet or guide 17 and insure an effective outdriving of such removed material and also to concentrate the air or gas on the fiber as it is forced through the tubular outlet. The air or gas also operates to expel the fiber from the outlet 17 simultaneously with the cleaning operation, and though the preferred air or gas applying device has been described and is shown it will be understood that the use of any air or gas applying means is contemplated having the operative characteristics just specified. The ducts 21 serve as distributing-channels for the air or gas, and the latter is delivered to the said channels under a high pressure, and as it expands in the tubular outlet or guide 17, which is in the form of an inclosing casing, it immediately resumes its normal pressure, and this expansion causes a dismembering or separation of the stalk or other matter from the fiber.

In some operations one machine or apparatus may be all that is necessary, but in other operations a number of similar machines may be demanded, and it is proposed, if found desirable, to arrange the machine in multiple series and have the tubular outlet or guide of one machine directed into the hopper or feeding inclosure 16 of another machine, and so on through the series. In the use of a series of machines the fiber will pass from one into the other and be subjected to similar operations and by such continuous treatment will, when it arrives at the outlet of the last machine of the series, be found to be in superior or better condition for manufacture.

The air or gas used in connection with the foregoing apparatus is compressed materially, so that when it is delivered to the crushed fiber it will operate to separate the latter and thoroughly separate or shatter the fiber, and the outward flow of the air removes the woody or foreign parts without removing any of the fiber. The fiber is sustained in a plume of air and under such conditions is thoroughly treated. This operation is in contradistinction to air under ordinary atmospheric pressure or atmospheric air under blower pressure, which is not sufficient to arrive at the result sought.

Having thus described the invention, what is claimed is—

1. The herein-described method, consisting of crushing or dismembering the stalk or woody part of hemp, jute, ramie, manila, or similar fibers, subjecting the crushed or dismembered stalk to the action of compressed air or gas, and maintaining the crushed or dismembered stalk in a confined current of the air or gas for a certain length of time.

2. The herein-described method, consisting of crushing or dismembering the stalk or woody part of hemp, jute, ramie, manila, or similar fibers, subjecting the liberated fiber to the action of compressed air or gas delivered thereto at invariable intersecting angles, and maintaining the crushed or dismembered stalk in a confined current of the air or gas for a certain length of time.

3. The herein-described method, consisting of crushing or dismembering the stalk or woody part of hemp, jute, ramie, manila or similar fibers, subjecting the liberated fiber to the action of compressed air or gas, and maintaining the liberated fiber in a confined current of the air or gas flowing in the direction of the length of the fiber and expanding about the latter, whereby the fiber is completely permeated by the air or gas to drive out small particles of leaves or other material that may cling thereto.

In testimony whereof I have hereunto set my hand in presence of two subscribing witnesses.

THOMAS GUNNI SAXTON.
